UNITED STATES PATENT OFFICE.

JOSEPH KASPE, OF CHARBIN, RUSSIA.

SAFETY DEVICE FOR ELEVATORS AND THE LIKE.

Application filed March 25, 1927, Serial No. 178,419, and in Germany February 13, 1926.

This invention relates to safety devices for elevators and the like and is an improvement on that type of safety devices in which, on the occurrence of a stretch or break in the 5 hoisting cable, brakes or the like are caused to grip the guide rails and bring the elevator to a stop.

One object of my invention is to provide a safety device of the class referred to, which 10 shall combine smoothness and reliability of action with cheapness of production and ease of control and supervision. Another object is the provision of means which will give warning of a stretch in the hoisting cable and to enable, to some extent, a compensation 15 of the slack by an adjustment of the safety device without thereby impairing the amount of safety.

My invention mainly consists in the provision, apart from the hoisting cable, of a 20 normally untensioned auxiliary cable in connection with a wedge piece on the elevator, and of special breaking means adapted to be operated by the said wedge piece so as to grip the guide rails with gradually increasing pressure.

The accompanying drawings illustrate the invention by way of example:

Fig. 1 shows the brake actuating wedge 30 and connected parts in part-sectional side elevation.

Fig. 2 is a side elevation of the counter weight.

Fig. 3 is a section on line III-III of 35 Fig. 1, partly broken away.

Fig. 4 illustrates the means for regulating the length of the cables.

Fig. 5 is a section through the rope pulleys for the hoisting and the auxiliary cables.

The cabin or platform of the elevator carries at its top a casing *a* in which a double sided wedge piece *b* is arranged. This wedge piece is provided with two passages *c* 45 through which the hoisting ropes or cables *c'* are loosely passed to be connected in known manner with the body of the elevator, and with two further passages *d* in which the ends of an auxiliary rope or cable *d'* are secured. The hoisting cable and the auxiliary cable are led in the usual manner over 50 rope pulleys *o*, *p*, at the top of the elevator frame, which pulleys are mounted on a driving shaft *q*. The pulleys *o* for the hoisting cable are fast while the pulleys *p* for the auxiliary cable are mounted loosely on

the said shaft. Both cable pass over these pulleys to grooved blocks *c*² and *i* respectively of the counterweight *l*, whence they are returned and again passed over the said 60 pulleys back to the elevator or the wedge piece respectively.

If now for any reason stretching of the hoisting cable, or a break should occur, the 65 down movement of the elevator would cause the wedge piece to rise in relation to the car by reason of its being in connection with the counter-weight by the auxiliary cable *d'*. Hereby the wedge piece jams itself between the rollers *m* of the tongue-like pivoted 70 brake levers *e* forcing them apart and thereby pressing the brake shoes *e'* gradually but tightly against the guide rails or bars *f* until the elevator comes to a stop. Spring *e*² tends to draw the brake levers *e* towards 75 each other and to normally keep the brake shoes out of engagement with the bars *f*. As long as only a small amount of stretch due to ordinary working stresses occurs, the slight grinding sound of the brake shoes on 80 the rails *f* give notice to the attendant who is able to compensate the slack in the hoisting cable by means of a regulating device, which will be referred to at a later stage of 85 this specification.

In the case of a stop by reason of a break of the hoisting cable of the elevator, the latter is held not only by the action of the 90 brake shoes but by the auxiliary cable *d'* also, which now has changed from the untensioned into the tensioned condition. This cable enables the elevator with its load to be moved to the next floor by turning down the bolt *g* thereby lowering the wedge piece *b* and releasing the brakes accordingly. 95 Even in such cases in which under some adverse conditions the emergency brake *e*, *e'* should not work to its full advantage, the cable *d* would give a sufficient amount of safety against accident. The fact of the 100 auxiliary cable running over the loose rope pulleys *p* on the driving shaft prevents its being placed under strain as long as the hoisting cable is in working order.

The device for regulating the length of 105 the cables as illustrated in Fig. 4 permits, contrary to the known arrangements, an exact observation of any stretch which may have occurred in the hoisting cable and thus constitutes a means for at all times ascertaining the working condition of the cable. 110 According to the drawing Fig. 4 the block

c^2 over which the hoisting cable c' runs, is mounted upon the counterweight l . A second block i for the auxiliary cable d' is attached to the block c^2 by means of a screw k and may be screwed up or down to compensate, to some extent, occurring differences in the length of the two cables.

It is to be understood that I do not wish my invention to be limited to the example shown and described, but that I may make any alterations according to requirements without thereby departing from the spirit of the invention as defined in and by the following claims.

15. What I claim is:—

1. The combination with an elevator and guide rails for the said elevator, of a hoisting cable attached to the elevator, an auxiliary cable normally untensioned, a wedge piece carried by the elevator and capable of relative movement thereto, said wedge piece being suspended from the counterweight by means of an auxiliary cable, tongue-like pivoted brake levers having brake shoes gripping loosely around the guide rails and extending with their inner ends near the apex of the wedge piece, means to suspend a counterweight from the hoisting cable and adjustable means in connection therewith to 20 which the auxiliary cable and the wedge piece are connected, the wedge piece being capable in case of a stretch in the hoisting cable to move upwardly in relation to the elevator and to force the free ends of each pair of brake levers apart so as to cause the application of the brake shoes to the guide rails.

2. In an elevator a safety device comprising a wedge piece suspended from the counterweight by means of an auxiliary cable, one or more sets of brake levers in co-operative relation to the said wedge piece, and means to vary the position of the wedge piece in relation to the said brake levers.

45. 3. In an elevator a safety device comprising a wedge piece movable in relation to the elevator and suspended from an auxiliary cable attached to the counterweight, brake levers adapted with their brake shoes to grip the guide rails of the elevator at the occurrence of a stretch or break in the hoisting cable, a regulating screw to lower the wedge piece after it has risen into its brake operating position by the occurrence of a 50 stretch or break in the hoisting cable.

55. 4. In an elevator a safety device comprising a wedge piece loosely suspended from

the counterweight by means of an auxiliary cable, a suspension block on the counterweight for the attachment of the hoisting cable, another suspension block for the auxiliary cable carried by the first named suspension block and adjustably connected thereto, a set of pivoted tongue-like brake levers adapted to be operated by an upward movement of the wedge piece in relation to the elevator at the occurrence of a stretch in the hoisting cable.

5. In an elevator a safety device comprising a wedge piece suspended from the counterweight by means of an auxiliary cable, a suspension block on the counterweight for the attachment of the hoisting cable, another suspension block for the auxiliary cable carried by the first suspension block, 70 screwable means to connect the second suspension block to the first suspension block, one or more sets of tongue-like pivoted brake levers adapted to be operated by an upward movement of the wedge piece in relation to 75 the elevator at the occurrence of a stretch in the hoisting cable.

6. In an elevator a safety device comprising in combination with guide rails for the elevator and a counterweight, a casing on the elevator, a double sided wedge piece, vertical passages through said wedge piece, a hoisting cable passing from the elevator loosely through the wedge piece over a driving pulley to a cable block on the counterweight and back to the elevator over another driving pulley, an auxiliary cable attached with both its ends to the wedge piece and passing over loose pulleys to a second cable block on the counterweight, the said second cable block being carried by the first cable block, means to vary the distance between the two cable blocks, tongue-like pivoted brake levers having their brake shoes adapted to grip around the guide rails of the elevator, and rollers on the free ends of the brake levers in close proximity to the apex of the said wedge piece so as to be forced apart when the latter ascends in relation to the elevator at the occurrence of a stretch 90 or break in the hoisting cable.

7. In a safety device for elevators as claimed in claim 4, a regulating screw on the wedge piece accessible from without and by means of which the position of the wedge piece on the elevator may be raised or lowered.

In witness whereof I affix my signature.
JOSEPH KASPE.
